UNITED STATES PATENT OFFICE

124,022

DESIGN FOR A CABINET FOR HOSE REEL UNITS

Alexander P. Fox, University City, and August Daniel Reisert, St. Louis, Mo., assignors to Lincoln Engineering Company, St. Louis, Mo., a corporation of Missouri

Application August 23, 1940, Serial No. 94,580

Term of patent 7 years

To all whom it may concern:

Be it known that we, Alexander P. Fox and August Daniel Reisert, citizens of the United States and residents of University City, St. Louis County, Missouri, and St. Louis, Missouri, respectively, have invented a new, original, and ornamental Design for a Cabinet for Hose Reel Units, of which the following is a specification, reference being had to the accompanying drawings, forming part thereof, in which:

Fig. 1 is a top plan view;

Fig. 2 is a front elevational view;
Fig. 3 is a side elevational view; and,
Fig. 4 is a perspective view of a cabinet for hose reel units, showing our new design.

The opposite ends and sides of the device are respectively the same.

We claim:

The ornamental design for a cabinet for hose reel units, substantially as shown and described.

ALEXANDER P. FOX.
AUGUST DANIEL REISERT.
